(57) **CLAIM**

The ornamental design for a light fixture, as shown and described.

DESCRIPTION

FIG. 1 is a perspective view of a light fixture in accordance with my design, illustrating movable portions;

FIG. 2 is a front elevation view of the light fixture in accordance with my design, illustrating movable portions;

FIG. 3 is a left-side elevation view of the light fixture in accordance with my design, illustrating movable portions;

FIG. 4 is a right-side elevation view of the light fixture in accordance with my design, illustrating movable portions;

FIG. 5 is a top plan view of the light fixture in accordance with my design, illustrating movable portions; and,

FIG. 6 is a bottom plan view of the light fixture in accordance with my design, illustrating movable portions.

The broken lines represent unclaimed portions of the light fixture.
